UNITED STATES PATENT OFFICE

161,271

FRUIT JUICE DISPENSER

Richard Linneman, Atlanta, Ga.

Application May 19, 1950, Serial No. 10,050

Term of patent 14 years

(Cl. D2—3)

To all whom it may concern:

Be it known that I, Richard Linneman, a citizen of the United States, residing at Atlanta, county of DeKalb, and State of Georgia, have invented a new, original, and ornamental Design for a Fruit Juice Dispenser, of which the following is a specification, reference being had to the accompanying drawings, forming a part thereof:

Fig. 1 is a front perspective view of a fruit juice dispenser, embodying my new design;

Fig. 2 is a top plan view thereof; and

Fig. 3 is a side perspective view thereof.

I claim:

The ornamental design for a fruit juice dispenser, as shown.

RICHARD LINNEMAN.
